UNITED STATES PATENT OFFICE.

CHARLES A. KUPFER, OF BURLINGTON, IOWA.

HAME-TUG.

SPECIFICATION forming part of Letters Patent No. 380,903, dated April 10, 1888.

Application filed May 23, 1887. Serial No. 239,162. (No model.)

To all whom it may concern:

Be it known that I, CHARLES A. KUPFER, a citizen of the United States, residing at Burlington, in the county of Des Moines and State 5 of Iowa, have invented a new and useful Improvement in Hame-Tugs, of which the following is a specification.

My invention relates to hame-tugs in which a plate with loops and recesses operates in conjunction with a tongued key; and the object of my invention is to provide a simple and convenient mode of fastening and unfastening the traces to the plate attached to the hame. I accomplish this by the mechanism 15 illustrated in the accompanying drawings, in which—

Figure 1 represents a full face view of my invention. Fig. 2 represents a longitudinal cross-section of the plate with the key in position as locked. Fig. 3 represents a view of the key. Fig. 4 is a vertical cross-sectional view of the key and plate.

Similar letters refer to similar parts throughout the several views.

In the drawings, A represents the plate in a hame-tug, made preferably of metal. It is provided with the rivet-holes D, by means of which it is attached with rivets to a leather backing. This plate A, further, has the slightly 25 inward curved loop I, by means of which the plate is attached to the hame, and also the elevated loop E, underneath and through which passes the trace. F is a loop in this plate for the back-band, and G represents a 30 loop for the belly-band.

B B represent a series of recesses or holes in the plate A, preferably square-cornered, which recesses have their sides partly beveled, as illustrated by C, so as to form a female dovetail. One end of this recess B is also slightly 35 beveled downward, as illustrated in Fig. 2 of the drawings by letter b.

Fig. 3 of the drawings represents the key J.

It consists of the inclined tongue H, the position of which is best shown in Fig. 2, the male dovetail J', and the part K, to which the trace L is attached. The under side of plate A is cut away, as illustrated in Fig. 2 of the drawings.

The operation of my invention is as follows: The plate A is in the first place attached to the hame through loop I, and by means of loops F and G to back-band and belly-band, respectively. I now pass the trace, to the end of which key J is attached, through the loop E, bring it forward, and insert the tongue and dovetail part of this key into the recess B and slide the key back, so that its dovetail part will engage with the dovetail part of the recess B. In this position it is locked, as shown in Fig. 2 of the drawings, the tongue H resting against the bevel b. This forms a secure fastening for the trace to the plate. In order to unfasten the same, part K of the key is raised and the tongue H passed forward under the plate A, whereby the dovetail part of the key is released and the key can be withdrawn.

What I claim as my invention, and desire to secure by Letters Patent, is—

1. In a hame-tug, the combination, with a 50 plate, A, having perforations B, said perforations B having female dovetailed portions C and beveled ends b, of a key, J, having male dovetailed portions J' and a tongue, H, substantially as described.

2. In a hame-tug, the combination, with a 55 plate, A, said plate provided with a depressed loop, I, an elevated loop, E, side loops, F and G, and a series of perforations, B, having dovetailed portions C and beveled ends b, of 60 a key, J, provided with a tongue, H, and beveled portions J', substantially as described.

CHARLES A. KUPFER.
